LOCK

Rollin Lester Gray, Chicago, Ill., assignor to The Illinois Lock Company, Chicago, Ill., a corporation of Illinois

Application January 25, 1940, Serial No. 315,559

4 Claims.

(Cl. 70—85)

My present invention is concerned with a lock, preferably operated by a key, having an associated locking bolt which may be conveniently assembled and secured in place after the locking mechanism has been installed. Such a lock may be advantageously used for various purposes, one suggestive place being in a desk drawer. In the description to follow, reference will be made to such an installation by way of exemplification.

In the accompanying drawing—

Figure 1 is a fragmentary vertical section through a steel desk showing the lock, illustrated in elevation, applied in place at the front end of a sliding drawer just below the desk top;

Fig. 2 is a view in perspective of the lock complete, per se;

Fig. 3 is a transverse section taken on line 3—3 of Fig. 1;

Fig. 4 is an enlarged side elevation of the lock with the rear end thereof broken away to exhibit a vertical section therethrough;

Fig. 5 is an enlarged fragmentary detail in section showing the parts in the position occupied when the bolt is being disconnected from the lock plug;

Fig. 6, which is a similar view, shows the bolt in the position it occupies when first inserted in the lock, preliminary to establishment of its pivotal connection with the plug.

The lock is here illustrated as applied to a metallic desk having a top T which overhangs a suspended molding M formed on its under side with an opening 7 for the reception of a vertically movable locking bolt. This apertured molding constitutes a keeper and will be so referred to hereinafter. The precise construction of the desk top and molding is of relative unimportance. Sheet metal forming spaced walls is suggested in the drawing.

Below the desk top is a drawer D having a vertical front wall 8 flanged rearwardly at 9 to provide a top wall for connection with a secondary wall 10 which defines with the front wall a narrow chamber wherein is accommodated the lock which will presently be described. The top wall is formed with an opening 10' adapted to register with the opening 7 in the keeper when the drawer is in its normally closed position.

The present lock is adapted to be mounted upon the front wall of the drawer wherein there is an opening 11 through which is extended the lock barrel B to occupy a position within the chamber just rearwardly of the front wall. A flange 12 which is affixed to the barrel at its outer end remains upon the outer face of the drawer front 55

wall. Against the inner face of this wall may be fitted a washer 13 adapted to receive pressure from a lock nut 14 which is in screw-threaded engagement with the threaded exterior 15 of the barrel. It is to be assumed, of course, that mounting of the lock in place will precede fitting of the secondary wall 10 to its final position.

The barrel body may be of conventional form in that it is provided with opposed flattened surfaces 16 which extend for the full length thereof and therebeyond in the form of spaced walls between which is a plate 17 at the inner end of the lock body. This plate is slightly spaced from the inner end of a rotatable plug P which is mounted within the barrel and adapted to be turned in response to operation of a proper key K which may be inserted within a key-way which is open at the front end of the lock. The details of construction of the plug and of the tumbler assembly carried thereby are unimportant to this invention, and so are not disclosed in detail. It may follow any of the usual constructions.

The narrow space to the inside of the plate 17 at the rear end of the barrel provides a guideway, open at opposite ends, for the reception and sliding motion therein of a shank 18 which extends in a plane transversely of the axis of the plug. As shown, one end of the shank is beveled to provide a cam at 19 and at a medial point lengthwise thereof it is formed with a transverse way, such as the slot 20 which may be extended, if desired, clear through to one edge of the shank. A head 21 is carried at the shank end opposite the bevel. The shank-head assembly constitutes the locking bolt which is adapted to be actuated by the plug when operated with the key therefor. So that motion may be communicated to the bolt, I provide an eccentric socket 22 opening out upon the rear end of the plug wherein there is received a hollow pin 23 with an outturned flange 24 at its inner end adapted to engage a stop ring 25 that is secured in place adjacent the outer end of the socket. As by means of a compression spring 26, confined within the hollow pin and exerting opposite thrusts against the plug and pin, the latter is normally urged to a protruding position beyond the rear end of the plug as far as permitted by engagement of the pin flange 24 with the stop ring 25. In this position the protruding end of the pin lies within the guide-way where it is adapted to enter the transverse slot 20 of the bolt.

When the bolt is first introduced in place by

insertion of its beveled end 19 into the guide-way, the normally protruding pin may be forced to recede when the bolt shank is further advanced therewithin. When it has been moved sufficiently to bring the slot 20 into register with the pin, the latter will snap outwardly into place therewithin to provide a pivotal connection between the plug and bolt so that with rotation of the former the bolt will be moved endwise within the guide-way. The bolt head, 10 which in one position will lie within the confines of the opening 10' in the top plate 9, is adapted to be advanced therefrom into the opening 7 of the keeper whereby the drawer is securely locked in its closed position. Access to the lock under such conditions is effectively barred. Should it be necessary or desirable to disassemble the bolt from the lock, then a small implement such as a nail N may be introduced through an opening 27 in the plate 17, this opening preferably lying opposite the pin 23 when the plug is in one extreme position of rotation, permitting the implement to advance, with consequent recession on the part of the pin until the bolt is free to be withdrawn. In order that the implement may be permitted to pass through the opening 21, a further opening 28 may be provided in the secondary wall 10 of the desk drawer, as shown.

The lock of my invention is particularly advantageous when installed in a hollow inaccessible space as herein described. Only when the bolt is retracted to permit opening of the drawer (or other locked structure) is it possible to effect removal of the bolt for any purpose whatsoever. The hole in the secondary wall of the desk front is generally unseen, and even if noticed would have no meaning for the ordinary user. In assembling the lock, the bolt is added last—after the drawer has been completed with the lock barrel installed inside the chambered front wall. The mere insertion and downward pushing of the bolt is all that is required, and once advanced to final position, the bolt is engaged by the pin which normally prevents its disassembly from the lock.

I claim:

1. A combination with two relatively movable structures one of which has a keeper, a lock comprising a barrel adapted for fixed attachment to the other structure and provided with a plug rotatable in response to operation of a proper key, there being a guide-way immovable with respect to the barrel extending transversely of the plug at one end thereof and substantially opposite the keeper, a bolt movable to engage or disengage the keeper and provided with a shank adapted for sliding movements within the guide-way, and means spring actuated to extend eccentrically from the plug end in sliding engagement with the shank adapted to establish a pivotal locking connection between the plug and bolt in a manner whereby the bolt is caused to advance toward or recede from the keeper in response to rotation of the plug consequent upon operation of a proper key.

2. In combination with two relatively movable structures one of which has a keeper, a lock comprising a barrel adapted for fixed attachment to the other structure and provided with a plug rotatable in response to operation of a

proper key, there being a guide-way immovable with respect to the barrel extending transversely of the plug at one end thereof and substantially opposite the keeper, a bolt movable to engage or disengage the keeper and provided with a shank adapted for sliding movements within the guide-way, spring actuated retractable means extended eccentrically from the plug end adapted to establish a pivotal locking connection between the plug and bolt in a manner whereby the bolt is caused to advance toward or recede from the keeper in response to rotation of the plug consequent upon operation of a proper key, there being an opening through one side of the guide-way and through the bolt shank opposite the locking connection therewith through which may be inserted an implement to press back the locking means whereby to free the bolt shank from its connection therewith.

3. In combination with two relatively movable structures one of which has a keeper, a lock comprising a barrel adapted for fixed attachment to the other structure and provided with a plug rotatable in response to operation of a proper key, there being a guide-way immovable with respect to the barrel extending transversely of the plug at one end thereof substantially opposite the keeper, a bolt movable to engage or disengage the keeper and provided with a shank having a cam end adapted for sliding movements within the guide-way, a way extended transversely of the shank, and spring actuated means extended eccentrically from the plug end adapted to recede when the cam end is pressed thereagainst and thereafter to advance into the way to establish a pivotal locking connection between the plug and bolt in a manner whereby the bolt is caused to advance toward or recede from the keeper in response to rotation of the plug consequent upon operation of a proper key.

4. In combination with two relatively movable structures one of which has a keeper and the other of which has spaced walls defining a chamber therewithin, a lock comprising a barrel adapted for fixed attachment to the other structure within the chamber thereof and provided with a plug rotatable in response to operation of a proper key, there being a guide-way immovable with respect to the barrel extending transversely of the plug at the inner end thereof and substantially opposite the keeper, a bolt movable to engage or disengage the keeper and provided with a shank adapted for sliding movements within the guide-way, a way extended transversely of the shank, a retractable pin extended eccentrically from the plug end into the transverse way adapted to establish a pivotal locking connection between the plug and bolt in a manner whereby the bolt is caused to advance toward or recede from the keeper in response to rotation of the plug, and spring means urging the pin outwardly into engagement with the bolt, there being an opening into the guide-way in line with the pin and a second opening through the adjacent structure wall in line with the first opening to permit the insertion therethrough of an implement wherewith to retract the pin to effect disengagement thereof from the locking bolt.

ROLLIN LESTER GRAY.
